a corporation of New Jersey

Application December 22, 1950, Serial No. 202,334

6 Claims. (Cl. 128—216)

1

The present invention relates to mixing containers for storage of segregated ingredients of liquid therapeutic preparations manipulatable to bring them together for admixture, one form being of such construction as to permit needle access for withdrawal of mixture contents and another form allowing direct hypodermic administration of mixture contents. Devices of the present invention constitute improvements on those disclosed and claimed in my respective copending patent applications Plural Compartment Admixing Vials for Segregated Storage of Ingredients of Solutions and Liquid Mixtures, Serial No. 160,988, filed May 9, 1950, and Single Dosage Disposable Hypodermic Syringe Ampules and Assemblies, Serial No. 202,333, filed December 22, 1950.

A general object of the present invention is to provide such mixing container structures, the parts of which are of simple construction, readily produced economically on a mass basis, and easily assembled together to form vials and/or syringe barrel structures subdivided into chambers for segregated storage of liquid therapeutic preparation components with intercommunication therebetween being readily permitted by gate means removable by fluid pressure developable in one chamber with application of manual pressure externally to a flexible wall thereof.

A more specific object of the present invention is to provide such devices which are characterized by the walls of one chamber being in the form of a collapsible tube so that when squeezed effectively will develop hydraulic pressure in a contained body of liquid component to force a partitioning plug out into an adjacent mixing chamber in which another component is temporarily housed, so as to bring the components together for admixture in an efficient and simple manner.

A further object of the present invention is to provide such a device in the form of a self-contained hypodermic syringe construction wherein certain hypodermic needle mechanism thereof may be manipulated in a simple manner to communicate with the interior for direct hypodermic administration of mixture contents upon squeezing a collapsible tube section thereof, following an initial squeezing operation creating hydraulic pressure in a liquid-containing chamber isolated from another chamber in which another preparation component is housed to unseat a partition plug permitting intercommunication and admixture of components.

Still another object of the present invention is to provide such hypodermic syringe construction in a form which permits aspiration by construct-

2

ing the flexible wall of the liquid storage chamber from elastic material and, preferably, as a collapsible tube made from elastic plastic material.

Other objects of the invention will in part be obvious and will in part appear hereinafter.

The invention accordingly comprises the features of construction, combination of elements and arrangement of parts, which will be exemplified in the construction hereinafter set forth, and the scope of the invention will be indicated in the claims.

For a fuller understanding of the nature and objects of the invention, reference should be had to the following detailed description taken in connection with the accompanying drawing, in which:

Fig. 1 is a side view, with parts broken away and in axial section, of an embodiment of the mixing container of the present invention employable to bring segregated components of liquid preparations together for admixture and from which mixture contents can be removed by a hollow needle pierced through a wall thereof, indicating in dot-dash lines compression of walls to create plug-unseating hydraulic pressure in one chamber;

Fig. 2 is a view similar to Fig. 1 showing the embodiment thereof in a favored inverted position after the partition plug has been driven from its seat by hydraulic pressure to bring the preparation components together, and indicating by a double-ended arrow longitudinal shaking to accomplish effective admixture;

Fig. 3 is a perspective view of the structure shown in Fig. 2 indicating puncture by a hypodermic needle of a wall of the container for removal of mixture contents;

Fig. 4 is a sectional view similar to Fig. 1 of another embodiment of the present invention equipped with hypodermic needle mechanism to permit hypodermic administration of mixture contents directly therefrom;

Fig. 5 is a view somewhat similar to Fig. 2 showing inversion of the embodiment of Fig. 4 after hydraulic pressure removal of the partition plug and indicating by a double-ended arrow longitudinal shaking for effective admixture of preparation components;

Fig. 6 is a sectional detail, with parts broken away, taken on an enlarged scale, of the syringe head of the device shown in Figs. 4 and 5, indicating manipulation of hypodermic needle mechanism to effect communication to the interior of the container; and

Fig. 7 is a perspective view similar to Fig. 3 of

the device shown in Figs. 4, 5 and 6, showing it ready for use in direct hypodermic administration of mixture contents.

Referring to the drawing, in which like numerals identify similar parts throughout, it will be seen that one vial embodiment of the present invention shown in Figs. 1, 2 and 3 may comprise a container 10, preferably in the form of a tubular structure, with one end 11 thereof defining a liquid storage chamber 12 and the other end 13 thereof defining a mixing chamber 14 for storage therein of another component of a liquid therapeutic preparation. In the embodiment shown in those figures, the end 11 of tubular structure 10 providing liquid chamber 12 is so constructed that a wall of the latter is flexible for reducing the cubic capacity of that chamber to create therein fluid pressure, more specifically hydraulic pressure when a body 15 of liquid component is confined therein, upon depression of the flexible wall. Preferably this is accomplished by forming that end 11 of the tubular construction 10 as a collapsible tube, the side walls of which are made of flexible sheet material and preferably are formed of elastic plastic material, such as one of the polyethylenes. Desirably the material employed for the collapsible tube section 11 is transparent, at least to a degree permitting inspection of contents and observation of interior parts of the device. Preferably the collapsible tube section 11 has formed integral therewith an end wall or head 16 having therein a relatively small axial passage 17 defined by a seat in which is frictionally seated a gate plug 18. The gate plug 18 may be, if desired, formed in the shape of a cup of relatively rigid plastic or rubber composition, preferably slightly larger than the passage hole 17 so as to be securely gripped in its seat temporarily to confine liquid body 15 in chamber 12. Collapsible tube section 11 is closed at its other end 19 in any suitable manner, such as by bringing opposed portions of the side wall together and adhering or heat-sealing them to each other, as indicated.

The other tubular section 13 of the container structure 10 preferably is in the form of an elongated tubular cup, as shown, having a closed end wall 20 with its lip 21 frictionally engaged over the head 16 of the collapsible tube section 11 and seating against a shoulder 22 provided by a circumferential flange 23 integrally formed with the side walls of the collapsible tube. In this manner the cup-shaped section 13 houses in its chamber 14 a body of another component of the therapeutic preparation, such as discrete particles 24 of medicinal solids. Preferably cup section 13 is made of any suitable rigid or semi-rigid material, such as metallic composition, glass, plastic, etc. Preferably it is formed of relatively rigid plastic material having at least sufficient transparency to permit inspection of contents.

In use and operation of the vial embodiment shown in Figs. 1, 2 and 3, the container 10 is charged with a body 15 of liquid component confined in the collapsible tube section 11, and solids 24 are loaded into the chamber 14, with those component materials isolated from each other by the partition formed by head 16 and the seated plug 18. Intercommunication between chambers may be brought about in a simple manner by squeezing inward on the side walls of the collapsible tube 11 in the direction of the arrows 25, 25, as shown in Fig. 1, which will create hydraulic pressure in chamber 12 to unseat gate plug 18 into mixing chamber 14. With further collapse

of the side walls of the tube 11, liquid 15 will be forced through passage 17 and the device may then be inverted, as shown in Fig. 2, to assure complete transfer of the liquid to mixing chamber 14 to bring it into contact with the solids 24. As indicated in Fig. 2, with the device approximately in the position suggested therein, thorough admixture of the liquid component with the solids is assured by shaking it longitudinally in the direction of the double-ended arrow 26 effectively to prepare the therapeutic preparation admixture.

Thereafter, mixture contents of container 10 may be removed by piercing a hollow needle 27 through a pierceable wall thereof. In the event that the cup section 13 is made of relatively rigid material with the collapsible tube section 11 being relatively more readily pierceable, the device as positioned in Fig. 2 may be reversed end-for-end to spill the mixture contents back into collapsible tube chamber 12. A hypodermic needle 27 may then be pierced through a wall of the latter near its bottom end 19 to withdraw mixture contents, as indicated in Fig. 3, and it is to be understood that Fig. 3 is not intended to dictate a substantially lateral position of the container during withdrawal of contents. Actually the closed end 19 of collapsible tube section 11 desirably may be oriented to a lowermost position so as to assure effective withdrawal of a maximum amount of the mixture contents.

Although it is proposed to confine a body 15 of liquid component in collapsible tube chamber 12 which substantially fills the same, fluid pressure sufficient to unseat plug 18 may be developed therein if that chamber should also contain a quantity of gaseous medium, such as air, or if the locations of the isolated liquids and solids were reversed with solids 24 confined in collapsible tube 11 with a body of gaseous medium. Further, should the walls of cup section 13 be of needle-pierceable material, of course mixture contents could be withdrawn therethrough.

In the embodiment shown in Figs. 4 to 7, inclusive, the cup section forming the mixing chamber is modified to have its outer end closed by suitable hypodermic needle mechanism. For this purpose, a tubular section 113 may be substituted for the cup section 13, preferably having at both ends thereof inturned circumferential flanges 28, 28. The inturned flange 28 at one end may be seated in a circumferential groove in the head 16 of the collapsible tube section 11 for further assurance of secure attachment thereto. The inturned flange 28 at the other end of tubular section 113 seats in a circumferential groove in a syringe head 29, with the latter closing off that end to confine within chamber 14 the solids 24.

The syringe head 29 may take one of the many forms proposed in my copending application for Single Dosage Disposable Hypodermic Syringe identified above, and thus, by way of example, may be in the form of a transversely-extending body having an outwardly-extending axially arranged neck 30 in which a longitudinally-extending socket 31 is formed, preferably by an axial bore closed off at its inner end by a needle-pierceable diaphragm 32. As proposed in that copending application, such hypodermic syringe head structure may be made from elastic plastic composition comprising a polyethylene so that diaphragm 32 will be needle-pierceable and when pierced by a needle the margins of the hole will

securely grasp the exterior surface of the needle to form a fluid-tight seal.

There is slidably mounted in the bore 31 a suitable support body 33 which may be formed of substantially rigid material, such as relatively rigid plastic or metal, preferably slightly oversize so as to be frictionally held in any desired position, such as an outer initial position, and circumferentially milled, if desired, as shown in Fig. 4. A double-ended hypodermic needle 34 is carried by and extends through the support body 33 with its inner end 35 initially arranged outwardly or short of diaphragm 32. The outer injecting end 36 of the needle 34 extends appreciably beyond the neck 30 as indicated. A capsule-like protective cover cap 37 is provided to house the outer end 36 of needle 34 and has its inner end 38 frictionally engaged in the outer end of bore 31 to be temporarily held securely in the initial position indicated in Fig. 4, with its inner edge juxtaposed to the outer face of support body 33. If desired, cap 37 may have stop means comprising a circumferential shoulder 39 adapted to abut against outer end 40 of neck 30 when slid inwardly in bore 31, to limit inward travel of needle support 33 so as to avoid any tendency for the latter to injure the diaphragm 32 after the inner needle end 35 has punctured the latter.

In operation of the hypodermic syringe embodiment shown in Figs. 4 to 7 inclusive, pressure will be applied externally to the flexible walls of the collapsible tube 11, such as in the direction of the arrows 25, 25 in Fig. 5. This, as explained above, will develop fluid pressure sufficient to unseat partition plug 18 into mixing chamber 14. The device will then be inverted to a position similar to that proposed in Fig. 2 or Fig. 5 to assure complete spillage of liquid component into the mixing chamber 14 to bring it into contact with the solids component 24, and thorough admixture is then assured by shaking the device longitudinally as indicated by the double-ended arrow 26.

Thereafter the protective cap 37 will be depressed or forced inwardly in bore 31 to cause it to push the needle support 33 forward therein almost to contact by its inner end 133 of diaphragm 32 so that the inner needle end 35 will pierce through the diaphragm, as indicated in Fig. 6, to bring the needle bore into communication with the interior of the container or its mixing chamber 14 and the body 41 of therapeutic mixture therein.

The operator will then withdraw protective cap 37 from the bore 31 so as to condition the device of Figs. 1 to 7 inclusive for hypodermic administrative use, as depicted in Fig. 7, with the outer injecting end 36 of the needle 34 exposed for thrusting into a patient's flesh. Should the operator desire thereafter some aspiration for a show of blood at the inner end 35 of the needle as viewed through the transparent elastic walls of collapsible tube section 11, slight depression on those walls in the direction of the arrow 42 of Fig. 7 and then release will effect such aspiration. Thereafter, injection of liquid mixture contents 41 of the device is effectively accomplished if it is held inverted in a position similar to that shown in Fig. 5 to assure a head of the mixture contents above the inner end of the needle, and squeezing pressure is applied externally of the flexible walls of the collapsible tube 11. Fluid pressure developed in the gaseous head above the liquid mixture 41 will expel the latter through the needle bore.

It is to be understood that many variations proposed in the above identified copending applications, or parts thereof, which are adaptable to logical employment in embodiments of the present invention within the scope of the claims of the present application are intended to be covered by the latter. It will thus be seen that the objects set forth above, among those made apparent from the preceding description, are efficiently attained and, since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A hypodermic syringe construction for storage of segregated ingredients of liquid therapeutic preparations to be administered thereby comprising, in combination, a collapsible tube of elastic plastic material closed at one end by a transverse wall to provide therein a liquid storage chamber, said wall having a relatively small opening therein defined by a seat, tubular means having its inner end fitted over the walled end of said collapsible tube to define therein a mixing chamber, a gate plug adapted to be frictionally held temporarily in said seat for isolating said chambers from each other temporarily and being capable of being forced into said mixing chamber by creation of hydraulic pressure in said liquid storage chamber with collapse of the walls of the latter when a body of liquid component of the therapeutic preparation is confined therein, means closing the outer end of said tubular means and having a longitudinally-extending socket closed off at its inner bottom end by a needle-pierceable diaphragm, a support body mounted in said socket, and a double-ended hollow needle structure supported by said support body, said needle structure having an outer injecting end extending outward therefrom beyond said end-closing means and an inner diaphragm-piercing end extending inward of said body toward said diaphragm while terminating short thereof with a passage extending from end to end, said diaphragm-piercing inner end of said needle and said diaphragm being adapted to be brought together to communicate the needle structure passage with the interior of said tubular means whereby said construction may serve after admixture of therapeutic preparation components therein as a hypodermic syringe for administration of mixture contents.

2. The hypodermic syringe mixing container as defined in claim 1 characterized by the provision of a removable cover mounted over the outer end of said needle and frictionally engaged into said socket outward of said body.

3. The hypodermic syringe mixing container as defined in claim 2 characterized by said support body being slidably mounted in said socket to carry forward said diaphragm-piercing inner end of said needle to puncture of said diaphragm, and said removable cover being slidably mounted

in said socket to push said support body forward therein upon depression to pierce the inner end of said needle through said diaphragm to communication with the interior of said container.

4. A hypodermic syringe for storage of segregated ingredients of liquid therapeutic preparations to be administered thereby comprising, in combination, elongated tubular means subdivided into two end chambers by a transversely-extending partition wall having an intercommunicating passage therein defined by a seat with the walls of said tube of at least one end thereof being formed of flexible material and with said end being closeable to confine a body of liquid component of the therapeutic preparation therein, means to close the other end of said tube to isolate therein other material component of said preparation and having a longitudinally-extending socket closed off at its inner bottom end by a needle-pierceable diaphragm, a double-ended hollow hypodermic needle means slidably mounted in said socket and frictionally held temporarily in the outer portion of the latter with its inner end located short of said diaphragm, means to slide said needle means forward in said socket to puncture of said diaphragm, and a gate plug adapted to be frictionally held temporarily in said seat for isolating said chambers from each other temporarily and capable of being forced into and loosely receivable in said second chamber by creation of hydraulic pressure in said first chamber upon collapse of walls of the latter with confinement therein of a body of liquid component.

5. A hypodermic syringe for the storage of segregated ingredients of liquid therapeutic preparations to be administered thereby comprising, in combination, a collapsible tube closed at one end by a wall having an outlet passage therein temporarily closed by a gate plug, said gate plug being capable of being forced out of the passage by creation of hydraulic pressure in said collapsible tube, cup means having its inner end fitted over the walled end of said collapsible tube to isolate therein another component of the preparation and to receive the liquid component from the collapsible tube for admixture of components when said gate plug is forced into said cup means by hydraulic pressure upon collapse of said tube, means closing the outer end of said cup means and having an axial bore therein closed at its inner end by a needle-pierceable diaphragm, a support element slidably mounted in said bore and frictionally held in an outer position therein, a hypodermic needle mounted through and carried by said support element with the inner end of said needle temporarily held spaced outwardly from said di-

aphragm, and slidable cap means frictionally mounted in the outer end of said bore in a removable manner protectively covering the outer end of said needle and adapted upon being slid forward in said bore to push said support element ahead of it to carry the inner end of said needle to puncture of said diaphragm and into communication with the interior of said cup means.

10 6. A hypodermic syringe for segregated storage of ingredients of liquid therapeutic preparations to be administered thereby comprising, in combination, a collapsible tube of elastic plastic material closeable at one end to confine a body of liquid ingredient therein and having its other end closed by a head provided with an axial outlet passage temporarily closed by a gate plug capable of being forced out of the passage by hydraulic pressure developable when the tube 15 is filled with confined fluid and its elastic walls are squeezed inwardly, a tubular extension having its inner end fitted to said head to provide a mixing chamber temporarily to isolate therein another ingredient, a syringe head closing the outer end of said tubular extension and having an axial bore therein closed at its inner end by a needle-pierceable diaphragm of elastic plastic material, a needle support frictionally receivable in said bore and slidably inwardly 20 therein to an inner position from an outer initial position, a hypodermic needle carried by and extending through said support with its inner end located short of said diaphragm when said support is at its outer initial position in said bore 25 and the outer end of said needle extending out of said bore when said support is at its inner position therein, and a cupped capsule having an open inner end protectively receivable of the outer end of said needle and frictionally receivable in a reciprocative manner in the outer 30 end of said bore beyond said support to push said needle inner end forward to puncture of said diaphragm and then to be removed for injective use of the outer end of said needle with the bore of the latter in communication with said mixing 35 chamber.
